UNITED STATES PATENT OFFICE.

GLENN MORE AND GUNNARD OBERG, OF JAMESTOWN, NEW YORK, ASSIGNEES TO THE BLACKSTONE MFG. CO., OF JAMESTOWN, NEW YORK, A CORPORATION OF NEW YORK.

GEARING FOR WASHING MACHINES.

Application filed February 3, 1926. Serial No. 85,760.

This invention relates to mechanism for operating washing machines and consists in the devices and combinations of devices herein illustrated, described and claimed.

5 In the accompanying drawings:

Figure 1 is a plan view of the device embodying our invention, detached from the machine.

Figure 2 is a side elevation of the same.

10 Figure 3 is a central, longitudinal section of the device, the section being in the vertical plane indicated by the dotted line 3—3 of Figure 1.

Figure 4 is a bottom plan view of the device, the bottom of the housing being removed.

Figure 5 is a view similar to Figure 4, showing the parts in a different position in the cycle of operation.

20 Figure 6 is an enlarged sectional view of a portion of the device shown in Figure 3, the section being taken in the plane of the dotted line 6—6 on Figure 3.

Figure 7 is a view of a portion of the device shown in Figure 6, the section being in the vertical plane of the dotted line 7—7 of Figure 1.

25 Figure 8 is a perspective view, detached, of one of the parts illustrated in Figures 4 and 5.

Figure 9 is a perspective view of the operating rack bar, showing a detail thereof.

Figure 10 is a plan view of a detail.

30 It will be understood by those skilled in the art how this mechanism is adapted to operate the operating element or oscillator within a washing machine tub, without illustrating the tub proper, but merely showing the relative positions of the parts by repro-

40 ducing the bottom of the tub. The operating mechanism is beneath the tub bottom and the operating shaft extends upwardly through the tub bottom to receive the tool or oscillator.

45 The wringer operating shaft likewise extends upwardly to the wringer, but on the outside of the tub.

50 By reference first to Figures 1 and 2, it will be noticed that the mechanism of the invention is enclosed within a housing A, the upper part 1 of which is secured to the lower part 2 in a familiar manner by nuts and bolts 3, 3. Rising from the top member 1 of the housing, is a tubular frame member 4 on the upper edge of which the bottom B of the

tub rests. Inside of this tubular frame member 4 is a tubular sleeve 5 and within the sleeve 5 is an operating shaft C. The tubular sleeve 5 is provided between its ends with an annular flange 6, the lower surface of 60 which forms a shoulder bearing for a suitable washer 7 which rests upon the bottom B of the tub, whereby the tub B is fastened firmly to the top of the frame 4.

65 The lower end of the sleeve 5 has suitable connection, in this instance screw threads 8, with the lower portion of the frame member 4; and the upper part of the sleeve 5 is provided with a suitable interior annular bearing 9 for the shaft C, which 70 shaft C projects upwardly beyond the upper end of the sleeve 5, and carries upon its upper end a member 10 of such exterior contour as to be complementary to the recess on the inside of the oscillator, agitator, or other 75 element 11 actuated from the shaft C.

75 The lower end of the shaft C is provided with a spur gear wheel 12, the hub 13 of which bears against the lower face of the frame member 4, and the sleeve member 5. 80 The wheel 12 is actuated alternately in opposite directions by means of a reciprocating rack bar 14, which latter is actuated from a crank arm 15 by means of a connecting link 16 pivotally secured to the crank arm at 85 17. Said crank arm is positioned on the lower end of a vertically disposed shaft 18, which carries a worm wheel 19 in mesh with and actuated by a worm 20 on a horizontal shaft 21. The shaft 21 projects outwardly 90 through the housing A and is provided with suitable means for operative connection with a motor; the means here illustrated being a pulley 22.

95 Having reference more particularly to Figures 4 and 5, it will be seen that the top 1 of the housing is provided with an inwardly projecting stud 23 upon which is pivotally mounted a swinging arm 24. This arm 24 is provided with an elongated, arcuate slot, indicated at 25, the walls of which are adapted to be engaged by an end 26 of the crank arm 27 on the lower end of a vertically disposed, rotatable shaft 28. The shaft 28 projects upwardly through a suitable 100 bearing 30 on the housing A, and upon its upper end, outside the housing, is secured a short lever 31. When the lever 31 is moved, the shaft 28 is rotated in the desired direction, and in operation, through crank 110

arm 27 and its slot engaging end 26, actuates the swinging arm 24.

Intermediate the pivotal connection of the arm 24 and slot 25 is a downwardly projecting stub shaft 32, which carries a roller 33, which roller 33 bears against the rear surface 34 of the rack bar 14. Upon the upper face of the rack bar 14 is a longitudinal shoulder lug 35 and on the swinging arm 24 is a downwardly projecting slightly curved flange 36. The rack bar 14 is so positioned that when its rear surface 34 bears against the roller 33, the shoulder of the lug 35 will bear against the inner surface of the flange 36 on the arm 24. Thus, as the arm 24 moves about its pivotal axis at 23, the rack bar 14 will have sliding contact with the flange 36, and a rolling contact with the roller 33 of the arm 24.

Again referring to Figure 4, it will be seen that the rack bar 14 is indicated as being enmesh with the spur gear 12 in one position of the rack, and by referring to Figure 5, it will be seen that the rack 14 is out of mesh with the gear 12. When the arm 24 is swung by the action of lever 31 from the position shown in Figure 5 to the position shown in Figure 4, it will be understood that the rack 14 will instantly mesh with the spur gear 12, and vice versa, and, also, that when the rack 14 is swung into the position shown in Figure 5, its reciprocating motion due to the action of the crank cam 15, may continue without any danger of it engaging with the spur gear 12, the rack oscillating back and forth between the roller 33 and flange 36.

Referring now to Figures 1, 2 and 3, it will be seen that the housing A is provided with a tubular, housing member 37, which extends upwardly from the housing top member 1, and that the supplemental housing 37 carries at its upper end a suitable bearing 38 for an extension of the shaft 18, which extension constitutes a wringer operating shaft 39. The shaft 39 is suitably connected at its lower end 40 to the shaft 18. The housing 37 for the wringer shaft also serves as a support for the wringer, not shown. The shaft 39 is provided on its upper end with suitable means for transmitting its motion to the wringer mechanism, said means in this instance being a bevel wheel 41. The top portion of the wringer shaft housing 37 is enlarged, as shown at 42, to accommodate the bevel gear 41 or other wringer operating mechanism employed. The outside of this enlarged part 42, or the upper portion of the housing 37, will be provided with a suitable apertured lug 43 to form a bearing support for a vertically disposed operating rod 44, the lower end of which will be suitably held in an apertured lug 45 on top of the housing. A handle H on rod 44 will be conveniently disposed for

the use of the operator to rotate the rod 44.

Upon the lower end of the rod 44 is mounted a lever 46, and a link rod 48 connects the two levers 31 and 46, so that by the operator moving the handle H in a desired direction, he will, through the rod 44, levers 46 and 31, and connected parts above referred to, swing the arm 24 in the desired direction to cause the rack 14 to mesh with or to be disconnected from the gear 12. When the wringer mechanism is to be put into operation by the use of appropriate means for that purpose, not forming a part of this present invention and therefore not illustrated herein, the motor actuating means will be thrown into action and the shaft 18 and its extension 39 will of course rotate, and the operator will actuate the handle H in the appropriate direction to cause the arm 24 to swing and disconnect the rack 14 from gear 12. Being thus in the position illustrated in Figure 5, the rack will travel idly, while the shaft 39 is actuating the wringer mechanism; and the washing element 11 within the tub will be idle, also, thus permitting the feeding of the garments from the tub to the wringer without danger of injury to the operator. It will be manifest, however, that where the wringing of garments from a source other than the tub of the washing machine is required, the rack 14 will be caused to mesh with the gear 12 and thus the washing of one batch of clothes and the wringing of a different batch may be carried on simultaneously.

On the wringer support and shaft housing 37, suitably spaced apart, are the apertured lugs 47 to which the tub is secured, by means of screw bolts 49 passing through the apertured and outwardly bent ends of the tub bands 50, as more clearly seen in Figure 10.

The upper part 1 of the housing A is shaped at one end to form a chamber or space for the worm 20 and worm gear 19, which space is covered by a cap plate 51, the bottom of this chamber being the horizontal wall 52 of the housing. In the cap plate 51 is the plugged oil hole 53, and the oil is allowed to flow into the housing chamber below the wall 52 by means of the oil hole 54 therein.

The chambers within the housing A are designed to be filled with a proper lubricant. In order that the same shall not rise up on the operating shaft C and work through the bearings, and flow outside the sleeve 5 and thus contaminate the wash water and cause injury to the clothes being washed, we have devised a very satisfactory method of oil circulation, as follows:

The top portion 1 of housing A is provided with a bottom or wall 55 for the frame member 4 and it is this wall into which the sleeve end is secured, as shown at 8 in Fig-

ure 6. Thus an elongated, annular chamber 56 is formed within the frame member 4 surrounding the sleeve 5. An elongated slot 57 is cut through the wall of the sleeve 5 near the upper part of this chamber 56 and a relatively large opening 58 is cut through the wall 55 (see Figs. 6 and 7). Thus any oil rising around the shaft C will pass through the slot 57 into the chamber 56 and find its way into the housing chamber 10 through the hole opening 58. To insure, further, that oil will not work up around the shaft C to a height above the slot 57, the interior of the sleeve 5 is greater in diameter 15 than the diameter of the shaft C intermediate its lower part and the bearing 9. The long bearing for the shaft C extends from the bottom of the slot 57 to its lower end, as clearly seen in Fig. 6.

20 The tool or washing element 11, actuated by the shaft C, is not herein claimed, as the same is made the subject matter of a separate application, and therefore need not be further described other than to state that it 25 is given a rotary oscillation in opposite directions by the mechanism described.

We claim as our invention:

1. A gearing for washing machines comprising a fixed support, an upright shaft 30 operatively mounted therein, a spur gear on said shaft, an arm pivotally mounted on the support and provided with two spaced apart, projecting members, a rack bar provided with a flange and adapted to reciprocate between said members, means for actuating the rack bar and manually operated means for actuating the pivoted arm, whereby the rack bar is shifted into and out of mesh with said gear, one of the projecting members of the pivoted arm being a flange with which the flange of the rack bar has sliding contact.

2. A gearing for washing machines, comprising an upright operating shaft, a spur gear on the lower end of said shaft, a reciprocating rack bar, means for actuating said rack bar, a swinging arm operatively associated with the rack bar, and manually operated means for actuating the swinging arm whereby the rack will be thrown into or out of mesh with said spur gear, said actuat-

ing means including a manually operated crank slidingly connected to the swinging arm.

3. A gearing for washing machines, comprising an upright operating shaft, a spur gear on the lower end of said shaft, a reciprocating rack bar, means for actuating said rack bar, a swinging arm operatively associated with the rack bar, and manually operated means for actuating the swinging arm whereby the rack will be thrown into or out of mesh with said spur gear, said actuating means including an arcuate slot 55 in the swinging arm, a crank arm engaging 60 in the slot and connections for the walls of said slot and connections for manually actuating the crank arm.

4. A gearing for washing machines, comprising an upright operating shaft, a spur gear on the lower end of said shaft, a reciprocating rack bar, means for actuating said rack bar, a swinging arm operatively associated with the rack bar, and manually operated means for actuating the swinging arm whereby the rack will be thrown into or out of mesh with said spur gear, said 70 swinging arm being provided with a roller 75 and with a downwardly projecting, curved flange, spaced from the surface of the roller, and said rack bar having line contact on one surface with the roller and being provided with a shoulder lug having contact with the said curved flange.

5. A gearing for washing machines, comprising an upright operating shaft, a spur gear on the lower end of said shaft, a reciprocating rack bar, means for actuating said rack bar, a swinging arm operatively associated with the rack bar, and manually operated means for actuating the swinging arm whereby the rack will be thrown into or out of mesh with said spur gear, said 85 manually operated means embracing a pair of levers, a link rod connecting said levers, a manually operated rod for actuating one 90 lever and operative connections between the other lever and the swinging arm.

In testimony that we claim the foregoing as our invention we affix our signatures this 26th day of January, 1926.

GLENN MORE.
GUNNARD OBERG.
